EMIL SCHLOSSBERG, OF NEW YORK, N. Y., ASSIGNOR OF ONE-HALF TO THE DECKER COMPANY, OF NEW YORK, N. Y.

BOWLING-BALL RETURNWAY.

1,145,803.

Specification of Letters Patent.

Patented July 6, 1915.

Application filed April 1, 1915. Serial No. 18,456.

To all whom it may concern:

Be it known that I, EMIL SCHLOSSBERG, a subject of the Czar of Russia, and a resident of the city of New York, borough of Brooklyn, in the county of Kings and State of New York, have invented a new and Improved Bowling-Ball Returnway, of which the following is a full, clear and exact description.

10 My invention relates to bowling ball returnways, and has reference more particularly to a ball returnway in which the balls are delivered on to a rack located at the front of the alley over and at the ball terminal.

An object of the invention is to provide a ball returnway which is simple, strong, efficient and inexpensive whereby balls of different diameter can be directed on to the 20 rack.

A further object of the invention is to provide a ball returnway wherein balls which did not reach the rack for some cause will be prevented from rolling toward the 25 pit of the alley.

A still further object of the invention is to provide a dusting device for the balls directed to the rack, which duster is preferably associated with the trap which is 30 adapted to direct the balls coming from the ballway on to the rack.

With the above and other objects in view, the nature of which will more fully appear as the description proceeds, the invention 35 consists in the novel construction, combination and arrangement of parts as herein fully described, illustrated and claimed.

In the accompanying drawings, forming part of the application, similar characters 40 of reference indicate corresponding parts in all the views.

Figure 1 is a side elevation of the front end of a ball returnway embodying my invention; Fig. 2 is a section on line 2-2, Fig. 1; Fig. 3 is a section on line 3-3, Fig. 1; and Fig. 4 is a perspective view of the trap with the dusting device.

Referring to the drawings, 5 represents the ball track which runs up in a curved 50 direction at the front end, as shown at 6, and abuts against a post 7 which carries a resilient member 8 above the track to rebound a ball coming thereagainst from the track 5. Located above the track 5 is a ball 55 rack 9 one end of which is in close prox-

imity to the curved portion 6 of the track. The rack 9 is supported from the ball track 5 by brackets 10 at a suitable distance to clear a large size ball. The end of the rack adjacent the curved portion carries a swinging trap 11 which is adapted to bridge the space between the rack and the curved portion. This trap is intended as a retarder for the balls running up the curved portion 6 of the track, and also as a guide for directing the balls coming from the curved portion 6 on to the rack 9. A resilient member 12 is associated with the trap to insure the quick return of said trap to its normal position, shown in full lines in Fig. 1.

A pair of swinging padded tongues 13 are secured to the under side of the rack 9 which will permit a ball to roll toward the post 7 but will prevent the ball from rolling back toward the pit if the ball did not pass beyond the trap 11 or did not reach the same. The tongues 13 are preferably located within the brackets 10 to give a neater appearance to the ball return. The reason for providing two tongues is to utilize the space between the tongues as a rack for duck-pin balls. This is obtained by dropping a large ball against the tongue 13, to the left hand of Fig. 1, to lock the same, while the right-hand tongue 13 is used as a trap for duck pin balls which are prevented from passing beyond the left-hand tongue by the large ball resting against it. Normally either of the tongues 13 will prevent the large balls from rolling toward the pit and thus force the attendant of the alley to run toward the ball to drive the same back on to the rack.

Straddling over the trap 11 is a brush-carrier 15 which has side openings 16 flanged at the opposite ends as shown at 17. Located within the carrier 15 is a semi-circular brush 18 provided at the ends with flanges 19 engaged with the openings 16 of the carrier, said brush facing the trap 11. It has a threaded stud 20 projecting through the carrier, and which stud carries a butterfly 21. Resilient members 22 engage the opposite sides of each flange. The upper springs 22 (see Fig. 3) are slightly stronger than the lower springs 22, so that normally a slight pressure is exerted by the upper springs on the brush. By means of the butterfly 21 the brush 18 can be adjusted within the carrier and also the pressure of the

22
 spring 22 on the brush varied. In addition to the brush 18 a flexible apron 23 is secured to the brush 18 to cover the side of the carrier facing the rack 9, whereby the passing 5 balls are dusted and the resistance of the brush and apron reduces the speed thereof when coming on to the rack.

As a ball 24 rolls up the curved portion 6 of the track 5 it raises the trap 11 which will 10 retard the movement of the ball 24 and the same will come in contact with the resilient member 8 which will cause the ball to rebound and roll back over the curved portion 6 of the track. The trap 11 being restored 15 to its normal position will direct the ball through the carrier 15, where the same will be brushed and simultaneously wiped by the apron 23 while passing through the carrier. The ball so delivered by the rack 9 will be 20 clean and ready for use.

When a large ball engages the left-hand tongue 13, which prevents the said ball from running toward the pit, a following ball coming to the rack is prevented from striking 25 the ball by the tongue, and, consequently, injury is prevented to the balls by the intact of one by the other by the provision of the spring tongue, as can be easily seen.

While I have described the principle of 30 operation, together with the device which I now consider to be the best embodiment thereof, I desire to have it understood that the device shown is merely illustrative and that such changes may be made as are within 35 the scope of the appended claims.

I claim:

1. In a ball returnway, a ball track which has its forward end curved upwardly, a rack 40 over said track adjacent the curved end thereof, a trap bridging said rack from the curved end of the track for directing the balls rolling back from said curved portion of the track on to the rack, and means between the rack and the straight portion of 45 the track mounted to allow a ball to roll toward the curved end of the track but preventing a reverse rolling movement.

2. In a ball returnway, the combination of 50 a ball track having its front end curved upwardly, a rack above said track, a trap normally bridging said rack with the curved portion of the track, and a swinging member carried by said rack and lying in the path of a ball on the track, said swinging member 55 being adapted to arrest the rolling movement of the ball after the ball has passed said member and tends to roll in a direction from the front to the rear of the track.

3. In a ball returnway, the combination of 60 a ball track the front end of which is curved upwardly, a rack above said track, a swinging trap bridging the rack with the curved portion of the track, and swinging tongues

suspended from said rack and adapted to be displaced by a ball rolling toward the curved 65 end of the track, said tongues having means preventing them from swinging in the opposite direction, substantially as and for the purpose set forth.

4. In a ball returnway, the combination of 70 a ball track having its front end curved upwardly, a rack above said track, a swinging trap normally bridging said rack with the curved portion of the track, a brush associated with the rack for brushing the balls 75 coming from the curved portion of the track to the rack, and a flexible apron associated with the brush to dust the balls after the same have been brushed.

5. In a ball returnway, the combination of 80 a ball track having its front end curved upwardly, a rack above said track, a gravitationally operable trap normally bridging said rack with the curved portion of the track, and a ball-dusting device carried by 85 the trap, said ball-dusting device including a flexible apron.

6. In a ball returnway, the combination of 90 a ball track having its front end curved upwardly, a rack above said track, a gravitationally operable trap normally bridging said rack with the curved portion of the track, a bracket associated with the trap, a brush resiliently suspended in said bracket over said track, and a flexible apron carried 95 by said bracket.

7. In a ball returnway, the combination of 100 a ball track having its front end curved upwardly, a rack above said track, a trap normally bridging said rack with the curved portion of the track; and a ball cleaning device on the bridging portion adapted to form a retarder for the ball coming from the curved portion of the track on to the rack.

8. In a ball returnway, a ball track which 105 has its forward end curved outwardly, a rack over said track adjacent the curved end thereof, a trap bridging said rack with the curved end of the track for directing the balls rolling back from said curved portion 110 of the track on to the rack, and a pair of spaced, padded tongues suspended from the rack toward the track, said tongues adapted to be displaced by the balls moving on the track to the curved portion thereof, said 115 tongues preventing the balls which have passed the tongue from retracting their movement on the track.

In testimony whereof I have signed my name to this specification in the presence of 120 two subscribing witnesses.

EMIL SCHLOSSBERG.
